Patented Nov. 4, 1913.

UNITED STATES PATENT OFFICE.

EARL C. WILCOXSON AND ERIC SWANSON, OF DENVER, COLORADO.

JEWELER'S VISE.

1,077,661.

Specification of Letters Patent.

Patented Nov. 4, 1913.

Application filed July 15, 1912. Serial No. 709,509.

To all whom it may concern:

Be it known that we, EARL C. WILCOXSON and ERIC SWANSON, citizens of the United States, residing at Denver, in the county of 5 Denver and State of Colorado, have invented certain new and useful Improvements in Jewelers' Vises, of which the following is a specification.

This invention relates to jewelers' vises, 10 the main object of the invention being to provide a vise of this character by which material or objects may be securely clamped and brought into any desired position for convenience in working upon them.

15 A further object of the invention is to provide a vise having a plurality of clamping faces for use in holding different kinds of materials or objects, and in which the vise proper may be removed from its support 20 and used as a hand vise.

The invention consists of the features of construction, combination and arrangement of parts hereinafter fully described and claimed, reference being had to the accompanying drawings, in which:—

25 Figure 1 is a vertical longitudinal section through a jeweler's vise constructed in accordance with our invention. Fig. 2 is a vertical transverse section on the line 2—2 of Fig. 1. Fig. 3 is a face view of the relatively stationary clamping jaw.

The vise comprises a body or support 1 having a clamping surface 2 and provided with a depending angular bracket 3 carrying 35 a screw 4 having a swiveled or stationary clamping head 5 for co-operation with the surface 2, whereby the device may be secured to a work bench or table.

40 The body or support 1 is formed with a casing sleeve or barrel 6 in which is fitted a jaw member 7, of circular form in cross section, and provided with a square or rectangular clamping head 8 at the forward end thereof. The said jaw member 7 is also 45 provided with a socket 9 opening through its forward end and closed at its rear end by a wall 10.

The member 7 is provided with a circumferential groove 11 receiving a locking or clamping pin 12. This pin 12 is movable vertically in a guide passage 13 formed in the body 1 and is formed with a lower beveled end 14 engaged by the beveled inner end 15 of a threaded pin or shaft 16 operating in a horizontal threaded opening 17 in

the body 2 and provided at its outer end with a hand lever 18. By turning this lever in one direction or the other the shaft 16 may be moved in or out to throw the beveled surfaces 14 and 15 into and out of engagement to thereby elevate the pin 12 to clamp the member 7 against longitudinal or rotary movement or to release said member 7 for rotary movement within or removal from the casing 6.

60 A second jaw member 19 is provided with a clamping head 20 corresponding in form to the head 8 and with a shank 21 which is fitted to slide telescopically within the socket 9, to permit the two clamping heads to be 65 adjusted with relation to each other. A key 22, preferably formed of round wire, is seated within a groove 23 in the base of the socket 9 and is provided with a bent end 24 70 engaging an opening 25 in the member 7 75 whereby it is held from longitudinal or rotary movement. In the shank 21 is formed a groove 26 receiving the key, thus forming a feathering connection between the two jaws whereby the jaw member 19 is permitted to slide within the jaw member 7, but is normally held from rotary movement relative thereto. It will be observed, however, that the key 22 is of less length than the groove 26 and terminates a distance in rear 80 of the forward end of the jaw member 7, from which it will be apparent that when the jaw member 19 is moved outward or forward to an abnormal position, i. e., to a point where the end 24 of the key or feather 22 85 passes out of the groove 26, the rear end of the shank 21 of said jaw member 19 will lie in advance of the key and be free for rotation in the forward end of the socket 9, thus allowing the jaw member 19 to be 90 rotated independently of the jaw member 7.

95 The jaw member 19 is provided with a bore or passage 27 through which extends an operating rod or shaft 28 having an annular groove 28' receiving an adjustable 100 retaining pin or screw 30 on the adjustable jaw member, by which the rod is permitted to have rotary movement but is held from longitudinal movement and yet may be detached when occasion requires. The forward end of the rod has a head 31 in which is slidably fitted a handle bar 32, whereby 105 said rod 28 may be operated. The rear end of the rod 28 is provided with threads 33 engaging a threaded opening 34 in the wall 10, 110

whereby the movable jaw may be adjusted in and out.

The rectangular head 8 of the jaw member 7 is provided along its margins with 5 clamping faces 35, 36, 37 and 38. The face 35 is preferably integral with the head, which is made of soft steel, while the faces 36, 37 and 38 are composed of detachable strips secured in position by screws or other 10 fastenings 39 and are preferably and respectively formed of hard steel, copper and indurated fiber, by which a series of clamping surfaces are provided for holding various objects or kinds of materials without injury and with the necessary gripping force. The head 20 of the jaw member is recessed to receive a clamping strip 40 detachably secured thereto by similar fastenings 41. By 15 making the strips 36, 37, 38 and 40 detachable interchangeable strips of different materials may be employed according to the character of the work to be handled.

In practice, an article or piece of material to be held may be placed between the 25 opposed gripping faces of the jaws and the movable jaw adjusted to clamp the same. The work may thus be held in a fixed position, or by turning the lever 18 to permit the pin 12 to drop the jaw member 7 may 30 be released to allow the two jaws to be turned within the sleeve 6 to bring the work to any angular position most convenient to the operator. By adjusting the jaw member 19 outward until it clears the key 22 and 35 then releasing the pin 12, the jaw member 7 may be turned to present any of its clamping faces for coöperation with the clamping face of the jaw member 19. At any time by releasing the pin 12 the jaw member 7 40 may be unlocked to permit of the removal of the vise proper from the holder so that it may be employed as a hand vise. It will thus be seen that the invention provides a 45 vise which affords manifold conveniences and which is therefore, of value to jewelers and others working under different conditions on different objects or materials.

We claim:—

1. A jeweler's vise comprising a support, 50 a jaw removably and rotatably mounted therein, a second jaw telescopically engaging the first jaw, one of said jaws having a plurality of clamping faces for coaction with the other jaw, means for slidably adjusting said jaws with relation to each other, means for holding the first jaw against removal and in any of its positions of axial adjustment, and a feathering connection between said jaws operative to permit sliding 55 motion of the second jaw to a determined degree and hold it against rotary movement independent of the first jaw, and adapted upon an abnormal outward movement of the second jaw to release said jaws for relative 60 rotary adjustment.

2. A jeweler's vise comprising a support, a hollow jaw adjustably and removably mounted in said support and provided with a circumferential groove and a plurality of clamping faces, a vertically movable locking pin supported by the support and adapted to be projected upward to engage said groove, to lock the jaw against both longitudinal and rotary movements, said pin having a beveled lower end, a second 70 jaw telescopically engaging the first jaw, connecting means between the jaws to normally permit said second jaw to have longitudinal without rotary movement and also to permit it to be released within its range 75 of longitudinal movement for relative rotary movement of the jaws, means for relatively adjusting said jaws, and a threaded pin upon the support at right angles to the locking pin, said threaded pin having a beveled end to engage the beveled end of the locking pin and provided at its opposite end with a handle.

3. A jeweler's vise comprising a support, a socketed jaw removably and rotatably mounted in said support, a single locking means for holding said jaw against removal and also in any of its positions of axial adjustment, a second jaw slidable within the socket of the first named jaw, connecting means between the jaws to normally permit said second jaw to have longitudinal without rotary movement and also to permit it to be released within its range of longitudinal movement for relative rotary movement of the jaws, and an operating screw journaled in the second named jaw and in threaded engagement with the first named jaw.

4. A jeweler's vise comprising a support, a hollow jaw removably and rotatably mounted in said support, said jaw having an external annular groove, an internal longitudinal groove and an opening intersecting the latter named groove, locking means for coöperation with the external annular groove of said jaw to lock the same against removal and in any of its positions of axial adjustment, a second jaw telescopically mounted in the first jaw and provided in its under side with a groove, a screw shaft journaled 105 in said second jaw and in threaded engagement with the first jaw, and a locking pin engaging the groove in the second jaw and internal groove in the first jaw and having a bent end inserted in the opening in the latter, said pin being of less length than the degree of longitudinal adjustment of the 110 second jaw.

5. A jeweler's vise comprising a support, a jaw removably and rotatably mounted therein and provided with an angular clamping head having a plurality of clamping surfaces, means for holding said jaw against removal and in any of its positions of axial adjustment, a second jaw having a clamping 115

surface for coöperation with any of the clamping surfaces of the first named jaw, means slidably connecting said jaws and normally holding the second named jaw against rotary movement independent of the first named jaw, while permitting said second named jaw to be adjusted to a predetermined position for independent rotation, and means for adjusting the jaws to move

their clamping surfaces toward and from 10 each other.

In testimony whereof we affix our signatures in presence of two witnesses.

EARL C. WILCOXSON.
ERIC SWANSON.
